UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed November 4, 1924. Serial No. 747,726.

This invention relates to typewriter mani-
folding, and particularly to the typing si-
multaneously of a record-bill or the like,
and duplicate copies thereof, and also miscel-
lanous other work-pieces. Typing of this
kind may be conveniently done on multiple-
ply paper-webs, the plies being sometimes
separate, but more generally connected in the
form of a fan-fold web and having suitable
10 forms printed thereon, the forms being torn
off from the main portion of the web after
typing, as set forth in the Wernery & Smith
Patent, No. 1,132,055, dated March 16, 1915.

In some cases, it is desired, in making out
15 such forms and simultaneous copies, to have
the heading and all the entries or typed items
appear on the original record-bill and dupli-
cate copies thereof, while only the heading
and certain single items of said entries ap-
20 pear on said miscellaneous other bills or
forms. Such an arrangement is especially
convenient for a mercantile establishment,
such as a mail-order house, when making out
an order or bill for a miscellaneous lot of
25 goods, which is of such a variety as to neces-
sitate the order being split up, so that the dif-
ferent items thereof may be conveniently sent
to different departments for execution. As
each item of a bill of goods generally occu-
30 pies only a single line of typing, it has been
found difficult to type the split orders or bills
at the same time that the original record-bill
and duplicate copies are typed upon the fan-
fold forms. This is because there must be
35 typed upon said record-bill or statement-ply
of web and its duplicate copies forming a
bookkeeping unit a complete schedule of the
items, whereas usually there must be typed
upon each of the split-order bills, sectional
40 or individual order-forms, only a single item.
It is therefore one of the features of the pres-
ent invention to overcome this difficulty and
enable each individual item to be typed singly
upon its own separate sectional or individual
45 order-form simultaneously with the typing
of a group of the same items upon the origi-
nal record-bill or statement-form and the
duplicates or bookkeeping forms thereof.

Instead of the single carbon-carrier usual-
50 ly employed in connection with continuous

billing machines of this type, two carbon-
carriers are employed, one behind the other,
the carriers being separately movable to en-
able one set of temporary or heading carbon-
sheets to be withdrawn by one of the carbon-
carriers after the bills have been partly typed,
while the other carbon-carrier, with its per-
manent carbon-sheets, is left undisturbed.

According to one form of the present in-
vention, a front carbon-carrier controls per-
manent carbon-sheets interleaved between
the plies of the duplicate copies, and also a
permanent carbon which lies between the
outermost or statement-ply and the top ply
of a number of split-order forms or individ-
ual order-forms interposed between said du-
plicate copies and the outermost statement-
ply. A rear carbon-carrier controls tem-
porary or heading carbons which are inter-
leaved between the plies of the split-order
individual order-forms. In typing upon
such plies, both of the carbon-carriers have
their respective carbons carried forward with
the webs to the printing line, and, upon
actuating the type, a heading may be writ-
ten on all of the sheets. The heading car-
bons interleaved between the split-order plies
are then withdrawn, and the platen may be
line-spaced to bring the forms to position for
printing the first item simultaneously upon
the original or statement form or bill and
duplicate or bookkeeping copies thereof, and
also upon only the first split-order or individ-
ual order-form. The platen is then turned
so as to bring all of the webs upwardly, and
the front statement-sheet and its underlying
permanent carbon are thrown forward so
as to permit the first split-order or individ-
ual order-form to be removed from its ply by
tearing the same off along a line of perfora-
tions provided for the purpose. The sheets
may then be returned to the printing line for
a second item to be typed, and the same proc-
ess as described in connection with the first
split or sectional order is carried out on as
many forms as there are separate items to
be typed. After all of the split-order forms
or sectional order-forms have been removed
from their plies, the remaining plies, that is,

the original order or statement and duplicate or bookkeeping copies thereof, are torn off from the main body of the web, against a cutting-off knife, and a new portion of the web is brought forward to printing position.

Another feature of the invention is the provision of means for severing the edges of the split-order or individual order portions of the web as the latter is brought forward so that said portions may be readily detached from the body of the web along transverse perforations or weakened margins.

According to one form of the invention, the front carbon-carrier controls only the carbons interleaved with the duplicate or bookkeeping copies, while the rear carbon-carrier controls carbons interleaved between the front or original statement or bill ply and each of the split-order or sectional order plies. In this form of the device the headings are printed on all of the sheets in the same manner already described. The rear carbon-carrier is then moved rearwardly to withdraw its heading carbons. A separate carbon-sheet is then placed between the front form or original bill and the first split-order form and a typing operation performed to print the first item of the bill upon the original bill, the first split-order form and each of the duplicate or bookkeeping copies.

The platen-cylinder is then turned so as to feed all of the forms upwardly, and the separate carbon-sheet is then placed between the first and the second split-order forms, so that the second item of the bill may be typed upon said second split-order form, the original bill and the duplicate or bookkeeping copies. This operation may be continued for as many split-order forms and copies of the original bill as the machine is capable of handling.

Another feature of the present invention is the provision of a novel form of fan-fold web in which certain portions may be readily detached from the main body thereof, after typing.

Other features and advantages will hereinafter appear.

In the accompanying drawings,

Figure 1 is a transverse section of the upper portion of a continuous billing type-writing machine, showing one form of the present invention.

Figure 2 is a similar view, showing the position of certain parts during operation of the machine.

Figure 3 is a cross-section of the platen and work-table of the machine, showing the position assumed by certain of the sheets while one of the plies of a work-web is being severed.

Figure 4 is a view of another form of the present invention.

Figure 5 is a cross-section of the platen and work-table shown in Figure 4, and illus-

trates one of the steps in the mode of operation of the machine.

Figure 5^a is a view of a detached carbon-sheet.

Figure 6 is a perspective view, showing 70 a fan-fold web, such as is used in the present invention.

Figure 7 is a top plan view of the machine, some parts being broken away and other parts dotted.

Figure 8 is a developed view of a fan-fold web such as may be used with the present invention.

Figure 9 is a view of a severed form, representing an original or statement-order-blank.

Figures 10, 11 and 12 represent split-order or individual order forms which have been severed from the main body of the web.

Figure 13 is a view of a fan-fold back forming a bookkeeping portion of the web-unit.

With particular attention directed to Figure 1, the reference numeral 10 indicates a revoluble platen fixed to a platen-shaft 11 which is journaled in a swing-frame 12, 90 mounted to swing about a pivot 13 in a carriage 14. An arm 15 of the frame 12 rests upon a cross-rod 16 of the carriage when the platen is in normal position, and a hooked finger-piece 17 engages around a pin 18, fixed to the platen-frame 12, to hold the platen normally against feed-rolls 19 and 20. Type 21 are driven against a ribbon 21' to type upon work-sheets run around the platen 10. A work-presenting frame, indicated generally at 22, extends rearwardly from the typewriter portion of the machine, just described, and includes suitable rails 23 upon which a front carbon-carrier 26 and a rear carbon-carrier 27 are slidably mounted in the 105 usual way. Handles 26' and 27' are attached to their respective carriers 26 and 27 to enable said carriers to be conveniently manipulated from the front of the machine.

A work-sheet unit, indicated generally by 110 the letter "W", and upon which suitable forms are printed, and comprising a plurality of superposed plies, either in the form of a fan-fold web or not, is led up from beneath the frame 22 over a work-support 28, 115 the sides of the plies being guided by means of a pair of gages 29. The work-sheet unit or web "W" is drawn forwardly over the frame 22, the plies thereof being interleaved with carbon-sheets carried upon the front 120 carbon-carrier 26 and the rear carbon-carrier 27, the platen-frame 12 being first thrown over so as to permit the leading portion of the web to be drawn straight forward between the platen 10 and a cutting-off knife 125 30. The platen-frame is then lowered so as to grip the webs between the platen and the feed-rolls 19 and 20. The usual hand-wheel of the platen may then be turned to bring the webs to the printing line for typing 130

5 a heading upon the forms, after which the platen-frame is again released and thrown over to permit the rear carbon-carrier 27 to withdraw its carbons. The front carbon-carrier 26 includes a series of carbon-sheet-holding fingers 31, 32, 33 and 34, mounted upon successively higher steps as customary. The three uppermost fingers, that is, 31, 32 and 33, have permanent carbons 31', 32' and 33' respectively interleaved with the web-plies of a fan-fold pack "E" forming a book-keeping unit, the latter occupying a position nearest the platen 10.

10 The outermost or original statement-ply of the web "W" is designated by the reference letter "A", and a plurality of split-order or sectional or individual order plies or forms are designated by the letters "B", "C" and "D". Said split-order plies occupy a position between the outer ply "A" and the fan-fold pack "E". The finger 34 of the forward carrier 26 has a permanent carbon 34' interleaved between the outer or original ply "A" and the split-order ply "B", and the rear carbon-carrier 27 carries carbon-holding fingers 35 and 36, for heading or temporary carbons 35' and 36' which are interleaved respectively between the split-order plies "B" and "C", and "C" and "D".

15 30 It will be noted that the split or individual order plies "B", "C" and "D" and their interleaved heading carbons 35' and 36' have passage between the carbon-holding fingers 33 and 34 of the forward carbon-carrier 26, and that the front or original statement-sheet "A" passes beneath the finger 34. By virtue of this arrangement the heading or temporary carbons associated with the rear carbon-carrier 27 may be readily withdrawn from 20 their associated forms by moving the rear carrier 27 rearwardly, after the headings have been printed upon all of the forms, and the original ply or statement form will always remain the outermost one of the pack, so that it will invariably receive ribbon-impressions of typed matter.

25 Referring to Figure 8, which represents a developed view of fan-fold stationery such as may be used in the present invention, it will be noted that the folding edges of the several plies comprising the web-unit are perforated at 37, so that they may be readily severed from one another. It will also be noted that the split or individual order forms 30 or plies indicated by the letters "B", "C" and "D" are perforated at 38 along their upper and lower margins, so as to permit each of the forms to be readily severed from its ply after typing. As the web is drawn forwardly 35 of the machine and around the platen, the side edges of the sheets "A", "B", "C" and "D" are severed along their side edges, by splitters 39 carried by the fingers 33, 34, 35 and 36, while the side edges of the fan-fold 40 pack or bookkeeping unit "E" remain un-

45 severed. After having printed the headings on all of the plies, and withdrawing the heading-carbon-sheets associated with the plies "B", "C" and "D", by moving the rear carbon-carrier 27 rearwardly, the platen-frame 12 is lowered and the sheets run to the printing line, so as to receive typewritten matter corresponding to a first item of an order. Due to the fact that there are no carbon-sheets now interleaved between the plies "B" and "C", and "C" and "D", no typed impressions will appear upon the split-order plies "C" and "D", but the split order "B", which lies immediately beneath carbon 34' of the original order form "A", will receive a typed impression, and also all of the plies of the fan-fold pack "E". The platen is next turned, so as to roll the plies upwardly until the perforations 38 of the ply "B" appear above the cutting-off knife 30. This portion of the ply is then torn off along said perforations 38, thus removing the same in the form of an individual typewritten sheet, the original or outer ply "A" and its carbon 34' having been first folded over toward the front of the machine to permit easy access to the ply "B" (see Figure 3). The platen is now turned in the opposite direction, so as to bring the sheets down to the second line of printing. The original sheet "A" and its carbon now overlie the split-order ply or form "C", and, upon operation of the type 21, the second item of the original ply or form "A" is typed thereon, and also upon each ply or form of the fan-fold pack "E". The same 50 cycle of operations is now carried out to remove the sheet "C" from the pack, and the platen advanced to print the third item. Thus it will be seen that the form "A" and the individual plies of the fan-fold pack "E" receive a composite schedule of the typed items appearing on each of the split-order forms, and that each of the latter has typed thereon only a single item, representing an order, which may be conveniently sent to its particular department for execution.

55 In Figure 4, there is shown a somewhat different arrangement for the fingers of the carbon-carriers, but the other parts of the machine are the same as already described. The web "W" is brought forwardly as described and is associated with a front carbon-carrier 39' and a rear carbon-carrier 40. The front carbon-carrier 39' has fingers 41, 42 and 43 mounted thereon, said fingers respectively holding permanent carbons 41', 42' and 43', which are interleaved with the plies of a fan-fold pack "E". The rear carbon-carrier 40 has fingers 44, 45 and 46, for holding heading or temporary carbons 44', 45' and 46', which are interleaved between an original or outer ply "A" and a plurality of split-order plies or forms "B", "C" and "D". It will also be noted that all of the carbons carried upon the rear carrier 40 and the plies "A", "B", "C" 60 and "D" are interleaved between the plies "B", "C" and "D", and the original or outer ply "A". The platen-frame 12 is lowered and the sheets run to the printing line, so as to receive typewritten matter corresponding to a first item of an order. Due to the fact that there are no carbon-sheets now interleaved between the plies "B" and "C", and "C" and "D", no typed impressions will appear upon the split-order plies "C" and "D", but the split order "B", which lies immediately beneath carbon 34' of the original order form "A", will receive a typed impression, and also all of the plies of the fan-fold pack "E". The platen is next turned, so as to roll the plies upwardly until the perforations 38 of the ply "B" appear above the cutting-off knife 30. This portion of the ply is then torn off along said perforations 38, thus removing the same in the form of an individual typewritten sheet, the original or outer ply "A" and its carbon 34' having been first folded over toward the front of the machine to permit easy access to the ply "B" (see Figure 3). The platen is now turned in the opposite direction, so as to bring the sheets down to the second line of printing. The original sheet "A" and its carbon now overlie the split-order ply or form "C", and, upon operation of the type 21, the second item of the original ply or form "A" is typed thereon, and also upon each ply or form of the fan-fold pack "E". The same 65 cycle of operations is now carried out to remove the sheet "C" from the pack, and the platen advanced to print the third item. Thus it will be seen that the form "A" and the individual plies of the fan-fold pack "E" receive a composite schedule of the typed items appearing on each of the split-order forms, and that each of the latter has typed thereon only a single item, representing an order, which may be conveniently sent to its particular department for execution.

and "D" pass beneath the carbon-carrying finger 43 of the front carrier 39, so that when run around the platen, said plies constitute the outermost plies of the web.

- 5 After having fed all of the forms or plies and their interleaved carbons around the platen and typed the headings thereon, the platen-frame is released, so as to permit the heading carbons associated with the forms 10 "A", "B", "C" and "D" to be withdrawn. The platen is then lowered and operated to carry the forms upwardly, and a single carbon-sheet 47 is inserted between the front form "A" and the split-order form "B" (see 15 Figure 4), after which the platen is reversely turned, so as to bring all of the plies to the printing line to receive the first typed item. It will be seen that such item will appear on the original or statement form "A", also on 20 the form "B", and on each of the forms of the fan-fold pack or bookkeeping unit "E", but no typing will appear on the sectional order-forms "C" and "D" owing to the fact that no carbons are interleaved therebetween. The 25 next operation is to turn the platen to bring the forms upwardly, and thus enable the carbon-sheet 47 to be removed from its original position and inserted between the split-order forms "B" and "C". Upon returning the 30 platen to the printing point for receiving the second item, said second item will be typed upon the outer or original form, all of the forms of the pack "E", and also upon the form "C", but will not be typed upon the form "B" 35 or "D" as will be readily understood. This mode of operation is carried out until all of the split-order forms have been typed, and it will be seen that, upon completion of such typing, the outer or original form contains a 40 composite schedule of all of the items, whereas each of the individual or split-order forms "B", "C" and "D" contain only one item each. Both of the carbon-carriers are next moved rearwardly so as to withdraw their carbons 45 from the typed forms, and the latter may then be severed from the body of the web by tearing off against the usual knife, adjacent the front of the platen.

Variations may be resorted to within the 50 scope of the invention, and portions of the improvements may be used without others.

Having thus described my invention, I claim:

1. The method of manifolding a succession of items of an order upon each of several bill-forms while typing the same items severally upon a sub-set of sectional order-forms with only one item upon each, including the steps of typing an item upon an outer sectional order-ply and simultaneously manifolding it upon the innermost bill-form plies of a multiple-ply web, leaving the intervening sectional order-plies untyped, then severing the outermost typed sectional order-ply 65 from the web and typing the next item upon

the second untyped sectional order-ply and manifolding it upon said innermost plies, then tearing off said second sectional order-ply and typing the third item upon the third untyped sectional order-ply and manifolding it upon said innermost plies, and effecting a line-spacing movement of the web after typing each of the items, thus simultaneously typing the items in a line-spaced group upon each of the innermost bill-form plies. 75

2. The method of manifolding a succession of items of an order upon each of several bill-forms while manifolding the same items severally upon a sub-set of sectional order-forms with only one item upon each, including the steps of typing an item upon an outer bill-blank ply and simultaneously manifolding it upon a sectional order-ply adjacent thereto and upon the innermost bookkeeping bill-form plies, all of which plies are connected in the form of a multiple-ply web, leaving the intervening sectional order-plies untyped, then severing from the web the carbon-typed sectional order-ply adjacent the outer bill-blank ply, to expose the next untyped sectional order-ply, and typing the next item upon the outer bill-blank ply, manifolding it upon the next untyped sectional order-ply and the innermost bookkeeping bill-form plies, then tearing off said sectional order-ply having a single item, to expose the next untyped sectional order-ply, and then typing upon the outer bill-blank ply, manifolding it upon the next untyped sectional order-ply and the innermost bookkeeping bill-form plies and tearing off said sectional order-ply having a single item, and effecting a line-spacing movement of the web after typing each of the items, thus simultaneously typing the items in a line-spaced group upon the outer bill-blank ply and upon each of the innermost bookkeeping bill-form plies. 95

3. The method of manifolding or concomitantly typing an original bill-sheet, a plurality of copies thereof, and a plurality of split-order slips, which consists of first manifolding a heading on all the bill-sheets and split-order slips by means of intervening carbons, withdrawing the carbons which interleave the split-order slips but leaving undisturbed the remaining carbons including the carbon which underlies the original bill-sheet, typing the first split of the order upon the original sheet and the copies thereof and upon the first slip, but not upon any plies whose carbons have been withdrawn, feeding the copies forward, detaching the first slip from the web and removing it from the machine, feeding the copies backward to the next typing line, manifolding successive items in like manner upon subsequent slips individually and successively removing them from the machine by forward and backward feeding of the copies, and finally withdrawing the carbon underlying the original sheet 139

and the carbons interleaving the copies thereof and feeding the copies forward, preparatory to detaching said original sheet and the remaining copies from the machine.

4. The method of typing one or more copies of a series of items with interleaved carbons on a pack of superposed work-sheets, and simultaneously individually manifolding with a single carbon successive items, separately from one another, on successive individual sheets in the pack, while typing the series of items complete on others of the superposed sheets, including the step of bringing all of the sheets to an accessible position after one item has been typed, and detaching the first single-item sheet so that no subsequent matter typed will appear on said sheet, presenting the next untyped sheet under the single carbon for manifolding the next item, returning the sheets to typing position to receive the next item, typing the next item, and repeating said steps until the complete series of items has been typed and the single-item individual sheets accordingly removed, leaving the remainder of the pack in the machine for final manipulation.

JESSE A. B. SMITH.
